UNITED STATES PATENT OFFICE.

HENRY A. WEIHMANN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,950, dated June 24, 1890.

Application filed April 15, 1890. Serial No. 348,090. Term of patent 3½ years.

To all whom it may concern:

Be it known that I, HENRY A. WEIHMANN, a citizen of the United States, residing in Philadelphia, in the county of Philadelphia and State of Pennsylvania, have invented and produced a new and original Design for Cane or Umbrella Handles, of which the following is a specification, reference being had to the accompanying drawing, forming part thereof.

In the drawing is shown a perspective view of a cane or umbrella handle illustrating my new design.

A is the body part, and is formed with a series of swelled portions, as indicated, relieved by highly-ornamental vertical bars H, alternating with bars of plain work G. The upper portion of the body part is slightly enlarged and depressed in the form of a cup or basin B, into which the upper ends of the

ornamental parts H extend. The middle part of the body is encircled by a double band C of plain surface. The lower part of the body is bounded by an annular band E of ornamental work, bounded at the top by a plain annular band D and at the bottom by a plain annular band F.

The handle is made of any suitable material.

Having now described my new design, what I claim as new, and desire to secure by Letters Patent, is—

The design for cane or umbrella handles, substantially as herein described and shown.

In testimony of which invention I have hereunto set my hand.

HENRY A. WEIHMANN.
